UNITED STATES PATENT OFFICE

HUGH L. MAHONEY, OF UNIONDALE, INDIANA

FENCE PROTECTOR

Application filed December 26, 1930. Serial No. 504,687.

This invention relates to a guard wire holder adapted to be used in connection with fences to provide a safeguard against damage by heavy or vicious animals and in general to serve the usual purposes of guard wires of this character. My invention consists in the provision of a novel device for supporting the guard wire in connection with a fence, and has for its principal object to provide a simple, inexpensive, durable and readily removable and interchangeable guard wire holder. A further object is to provide such a holder which will afford maximum convenience in installation and removal. Other and more limited objects will appear as the specification proceeds.

Fig. 1 is a perspective view of a fence showing my invention in its position of use; Fig. 2 is an end view showing one phase of the preferred method of installing or attaching my improved guard wire holder; and Fig. 3 is an end view showing the same in position.

In the drawings I have shown a mesh fence 10 of usual construction supported by means of posts 11 and attached to such posts as by staples 12. My improved wire holder consists of two bars 13 and 14. Each of these bars is provided with notches 13^a and 14^a at one end. The bars are pivoted together at 15 by means of a suitable rivet. At the opposite ends of the bars 13 and 14 I provide slots 13^b and 14^b. Communicating with said slots are openings 13^c and 14^c constituting with such slots at an end of each bar a T slot. From the drawings it will be observed that the bar 13 is longer than the bar 14. This relative length serves the double function of positioning the guard wire 16 at substantially the level of the top strand of the fence 10 and permits the attachment of the bar 13 to a lower strand and the subsequent rotation of the bar 14 therewith for attachment to the top strand and simultaneous locking of the guard wire 16 between the notches 13^a and 14^a as clearly indicated in Fig. 3. It will also be observed that the pivot point 15 is positioned to one side of the center of each of the bars, that is, toward the side which contains the notches. This permits the use of shallower notches than would otherwise be

possible. The openings 13^c and 14^c are placed on the sides of the bars which are to be on the lower side when the device is in position of use whereby to avoid the disconnecting of the bars from the strands of the fence 10 due to action of gravity if said strands move in 55 the slots 13^b and 14^b. In order to secure this result it is necessary that the opening 13^c and the notch 13^a be placed on opposite sides of the bar 13 while the opening 14^c and the notch 14^a are placed on the same side of the 60 bar 14.

While I have shown and described the preferred embodiment of my invention I wish it understood that various departures in construction from the embodiment illustrated 65 may be made and that I am limited only in accordance with the appended claims.

Having thus described my invention, what I claim is:—

1. A guard wire holder for fences including a pair of bars pivoted together, notches adjacent the pivot point adapted to hold a guard wire, and T-slots spaced from said pivot point and adapted to engage spaced wires of a fence, one of said T-slots being 75 from said pivot point a greater distance than the other, whereby the shorter bar may be pivoted past the longer when the latter is connected to a wire of a fence.

2. A guard wire holder for fences including a pair of bars, each of said bars having a notch adjacent one end, the opposite end of each bar being provided with a slot, an opening communicating with each of said slots for entrance of a wire, said notch and said opening being on the same edge of one of said bars and on opposite edges of the other bar, said bars being pivoted together adjacent said notches.

3. A guard wire holder for fences including a pair of bars, each of said bars having a notch adjacent one end, the opposite end of each bar being provided with a slot, an opening communicating with each of said slots for entrance of a wire, said notch and said opening being on the same edge of one of said bars and on opposite edges of the other bar, said bars being pivoted together adjacent said notches, the pivot point being on one side of the center of at least one of said bars.

4. A guard wire holder for fences including a pair of bars, each of said bars having a notch adjacent one end, the opposite end of each bar being provided with a slot, an opening communicating with each of said slots for entrance of a wire, said notch and said opening being on the same edge of one of said bars and on opposite edges of the other bar, said bars being pivoted together adjacent said notches, the pivot point being off-centered toward the same edge of one of said bars which contains the notch.

5. A guard wire holder for fences including a pair of bars flat throughout their length and pivoted together, notches adjacent the pivot point adapted to hold a guard wire, and T-slots spaced from said pivot point and adapted to engage spaced wires of a fence, one of said bars having its T-slot and notch on the same side, the other bar having them on opposite sides and being enough longer than said first bar to permit it to pivot past said other bar when the T-slot thereof is engaged over a wire.

25 In testimony whereof, I hereunto affix my signature.

HUGH L. MAHONEY.
